UNITED STATES PATENT OFFICE.

FRANK H. QUADE, JR., OF FRESNO, CALIFORNIA.

AUTOMATIC PAPER-FEED FOR PRINTING-MACHINES.

1,269,304.

Specification of Letters Patent. Patented June 11, 1918.

Application filed April 20, 1917. Serial No. 163,457.

To all whom it may concern:

Be it known that I, FRANK H. QUADE, Jr., a citizen of the United States, residing at Fresno, in the county of Fresno and State of California, have invented certain new and useful Improvements in Automatic Paper-Feeds for Printing-Machines, of which the following is a specification.

This invention relates to means for feeding paper to the printing mechanism of printing machines. One object of the invention is to provide means whereby the pile of sheets will be fed automatically toward the transferring mechanism so that the uppermost sheet in the pile will always be in position to be engaged by the transferring mechanism, and a further object of the invention is to provide simple means whereby the movement of the apparatus may be accurately adjusted to the thickness of the sheets of paper being fed to the printing mechanism.

The invention is illustrated in the accompanying drawings, in which:

Figure 1 is a perspective view of a printing machine having my improved paper feed mechanism in position thereon;

Fig. 2 is an enlarged view partly in section and partly in elevation of the paper feeding mechanism showing the same in the position assumed when a sheet of paper is being transferred to the conveyer;

Fig. 3 is a similar view showing the parts in the position assumed when the top sheet is about to be engaged;

Fig. 4 is a plan view of the apparatus;

Fig. 5 is an enlarged detail plan view of the adjustable actuating lever.

In the accompanying drawings is illustrated a frame 1 upon which is supported a printing roller mechanism 2 adapted to cooperate with a reciprocating type bed which is not shown. Upon this frame is also mounted driving mechanism which may be actuated by an electric motor supported upon the frame and comprises a driving shaft 3 having an eccentric or cam 4 at one end which is connected by a link 5 with an angle lever 6 on the frame, the said angle lever transmitting movement through a connecting rod 7 to a crank arm or lever 8 and the said crank arm or lever having pivoted thereto one end of a pitman 9. A vibratory lever 10 is also mounted upon the frame and operatively connected with the main shaft 3, the upper end of this lever being connect-

ed with the type bed and its lower end, in the present instance, being connected with the piston rod 11 which extends into the cylinder 12 of an air pump and is connected with the piston working in the said cylinder. The several parts thus far mentioned may be of any preferred form or arrangement and are illustrated herein in a more or less conventional manner and only to such an extent that the improvements forming the present invention may be readily understood.

The sheets of paper to be fed to the printing mechanism, of which the train of rollers indicated at 2 forms a part, are piled upon the table or board 13 and are transferred singly and successively to conveyers 14 by which they are carried to and delivered into the printing mechanism. The board or table 13 is pivotally attached at its forward end to a bracket 15 slidably engaged around a vertical bar or post 16 which is rigidly supported at its lower end upon a cross rod 17 which is rigidly secured at its ends to the supporting arms 18 projecting from the end of the main frame.

As just stated, the board or table 13 is pivoted at one end to a bracket 15 so that it is capable of a swinging movement in a vertical plane and a slotted lug or plate 19 depends from the board or table past a rigid arm 20 projecting from the bracket 15, a holding bolt 21 being inserted through said slotted plate into said arm so as to secure the table at any angle in which it may be set. By giving the table a slight inclination, the sheets of paper will be caused to break from the stock against the guide board 22 so that only a single sheet will be picked up by the transferring mechanism. The table is constructed with longitudinal slots 23 and transverse slots 24 which receive set screws or similar devices 25 by which end and side boards 26 are adjustably secured upon the table. These boards will bear against the edges of the sheets of paper and, as they are adjustable, will permit the operator to arrange the device so as to support sheets of any dimensions in proper alinement. In actual practice, I so adjust the end or back board and set the table at such an angle that the upper portion of the back board will be at a distance from the front board 22 slightly less than the length of the sheets, the result being a buckling of the upper sheets and a slight separation of the same so that but

one sheet will be taken up at a time. The bracket 15 is slidably mounted upon the posts or standards 16 and at one side fits entirely around the post and at the opposite side of the machine may be constructed with hooks 27 which span the post or standard but are capable of sliding movement thereon. It will be understood that the hook 27 is merely an alternative cheaper construction 5 and that the ring or collar form may be employed at both sides of the machine. The bracket 15 serves as a base or abutment to receive the thrust of the supporting arm 20 and the said arm may, if preferred, be formed as an integral part of said bracket. 10 The gage board 22 is carried by lugs or brackets 29 which are secured upon the cross bar 17 and the rod 30 connecting the upper ends of the posts 16. The bracket 15 is provided at its lower edge with a forwardly projecting arm 31 which extends around the post 16 and beyond the same and is constructed at its extremity with a threaded bore to engage around the worm 32. This 15 worm 32 is mounted at its lower end in a forward extension of the bracket 28 which is secured on the post 16 just above the rod 17 and below the said bracket a ratchet wheel 33 is rigidly secured upon the worm 20 so as to rotate therewith. This ratchet 25 33 is partly inclosed by a hood 34 which is mounted loosely upon the lower end of the worm. A lever 35 is loosely pivoted upon the worm immediately adjacent the upper 30 side of the hood 34 and the rear end of the pitman 9 is pivoted to this lever so that when the pitman is reciprocated the lever will be vibrated. The free end of the lever projects beyond the edge of the hood 34 and 35 carries a pawl 36 which is adapted to engage the teeth of the ratchet wheel or disk 33 and thereby impart motion to the said ratchet wheel or disk and the worm 32 to which it is rigidly secured. By referring to Fig. 5, 40 it will be noted that in one position of the lever 35 the pawl 36 will ride upon the rim of the hood 34 and it will, therefore, be obvious that, by properly adjusting the hood, more or less of the stroke of the pawl will 45 be over the surface of the hood, and therefore, out of engagement with the ratchet wheel. It is thus possible to adjust the device to the thickness of the sheets of paper being fed to the printing mechanism without 50 dismantling any part and without requiring a complicated structure. The bracket 28 is so formed as to pass around the worm 32 and an arm 37 is extended outwardly and downwardly from the said bracket, the 55 60 downwardly extending extremity of the said arm being split and having one branch 38 bent over and toward the top of the hood 34 so as to form a pointer arranged to coöperate with a scale 39 on the hood while the 65 other branch of the said arm is carried

downwardly past the rim of the hood and receives a set screw 40 carried by a clamping bar 41 which extends up into the hood at the inner side of the rim thereof. A thumb nut 42 mounted upon the set screw 40, may be 70 turned home against the branch 43 of the arm 37 so as to effect a clamping engagement between the rim of the hood and the arm 41 whereby the hood will be held positively in any position in which it may be set. 75

At the inner end of the lever 35 is secured a beveled gear 44 which is disposed loosely upon the lower end of the worm 32 but is rigid with the lever so that it will follow the movement of the lever but will not actuate 80 the worm. In the side of the bracket 28, a stub shaft 45 is journaled and upon the inner end of said shaft is a beveled gear 46 which meshes with the gear 44 so that the vibrations or reciprocations of the pitman 9 and 85 the lever 35 will be transmitted through the gears to the shaft 45, said shaft carrying a crank arm 47 which acts through a connecting rod 48 to operate the mechanism for transferring the sheets from the table 13 to 90 the conveyers 14. I prefer to employ suction tubes 69 to engage the sheets and directly transfer them, said tubes being connected with the pump 12 as will be readily understood. 95

It is thought the operation will be readily understood from the foregoing description taken in connection with the accompanying drawings. As the pitman 9 moves rearwardly, the pawl 36 will be moved into engagement with the ratchet wheel or disk 33 and will actuate the same to the extent permitted by the hood 34. This movement of the ratchet disk will be transmitted directly to the worm 32 and the rotation of the worm 105 will, through its engagement with the projection 31 of the bracket 15, cause upward movement of the said bracket and the table carried by the same, thereby lifting the table and the paper piled upon the same a distance equal to the thickness of one sheet of paper. As the pitman 9 and lever 35 move forwardly, the pawl will ride onto the rim of the hood and the initial portion of its succeeding rearward movement will 110 be on the rim of the hood out of engagement with the ratchet. Obviously the extent of the movement of the ratchet will be determined by the adjustment of the hood more or less along the arc described by the pawl 115 in its movement.

In Figs. 2 and 3, I have shown a portion of an air blast pipe 200 arranged to deliver air to the pile of sheets. This gentle flow of air keeps the sheets slightly separated and also serves to overcome the static electricity in the paper. 125

The improved mechanism herein disclosed is compact and is composed of few parts which are simple in construction and direct 130

and efficient in operation. By the use of my invention, the sheets of paper will be automatically lifted a distance equal to the thickness of a single sheet after each removal of a sheet and by very slight adjustment the apparatus may be adapted to any thickness of paper. The feeding mechanism actuated by the gears 44 and 46 transfer a sheet of paper from the table to the 10 conveyer during the interval of rest for the ratchet and the elevating worm. Moreover, it is possible to feed thick cards or thin paper with equal facility.

Having thus described the invention, what 15 is claimed as new is:

1. In an apparatus for the purpose set forth, the combination of a support, a table movable vertically on the support, a worm operatively connected with the table, a 20 ratchet disk secured to the lower end of the worm, a hood disposed concentrically with the worm and the ratchet disk and partly inclosing the disk, an arm fixed to and extending from the support over the hood, 25 means carried by the free end of said arm to engage the hood and secure the same in a set position, a lever mounted concentrically with the worm and extending over the hood and beyond the rim of the same, means 30 for oscillating said lever, and a pawl carried by the lever and arranged to ride on the rim of the hood and engage the edge of the ratchet disk.
2. In an apparatus for the purpose set 35 forth, the combination of a support, a table movable vertically on the support, a worm operatively connected with the table, a ratchet disk secured to the lower end of the worm, a hood disposed concentrically with 40 the worm and the ratchet disk and partly inclosing the disk, said hood being provided with a graduated arcuate scale on its upper surface disposed concentrically with the worm, an arm fixed to and extending from 45 the support over the hood, a pointer carried by said arm and depending therefrom to the top of the hood and coöperating with said scale, a lever mounted concentrically with the worm and extending beyond the 50 rim of the hood, means for oscillating said lever, a pawl carried by the lever and arranged to ride on the rim of the hood and engage the edge of the ratchet disk, and means carried by the free end of the fixed 55 arm to engage the rim of the hood and secure the hood in a set position.
3. In an apparatus for the purpose set

forth, the combination of a support, a table movable vertically on the support, a worm operatively connected with the table, a 60 ratchet disk secured to the lower end of the worm, a hood disposed concentrically with the worm and ratchet disk and partly inclosing the disk and having a rim depending past the edge of the disk, an arm fixed 65 to and extending from the support over the hood and having its extremity projecting past the rim of the hood at the outer side thereof, a clamping plate disposed at the inner side of the rim of the hood, a clamping bolt carried by said plate and extending through the extremity of the fixed arm, means coöperating with said bolt and the end of the arm to clamp the rim of the hood between said arm and said plate, a 70 lever mounted concentrically with the worm and extending beyond the rim of the hood, means for oscillating said lever, and a pawl carried by said lever and arranged to ride on the rim of the hood and engage the edge 75 of the ratchet disk.

4. In an apparatus for the purpose set forth, the combination of a support, a table movable vertically on the support, a worm operatively connected with the table, a 80 ratchet disk secured to the lower end of the worm, a hood disposed concentrically with the worm and ratchet disk and partly inclosing the disk, said hood being provided with a graduated scale on its upper surface dis- 85 posed concentrically with the worm, an arm fixed to and extending from the support over the hood and having its outer end divided longitudinally, one branch of said divided portion being turned to the top of 90 the hood to coöperate with the scale thereon and the other branch of the said divided portion of the arm depending past the rim of the hood, a clamping plate disposed at the inner side of the rim of the hood, a 100 clamping bolt carried by said plate and extending through the depending portion of the fixed arm, means coöperating with said bolt whereby the rim of the hood may be clamped between said plate and the depending portion of the arm to hold the hood in a set position, a lever mounted concentrically with the worm and extending beyond the rim of the hood, and a pawl carried by said lever and arranged to ride on 105 the rim of the hood and engage the edge of the ratchet disk.

In testimony whereof I affix my signature.

FRANK H. QUADE, JR. [L.S.]
